THEW SHOVEL COMPANY, OF LORAIN, OHIO, A CORPORATION OF OHIO

GRAPPLE

Application filed May 22, 1930. Serial No. 454,695.

Our invention relates to an improvement in grapples. It relates, particularly, to a grapple made up of a plurality of tapered blades which, when open, form a means for gathering the material to a centralized point and then, upon closing form a means for grasping it firmly whereby it may then be conveyed to any desired location.

Previous grapples of this type have been 10 of such nature that, when the blades were moved toward each other to grasp the material, the points of the blades have moved inwardly and upwardly to simultaneously penetrate and lift the material during closing of 15 the grapple. Such action is undesirable in attempting to pick up a load of material such, for instance, as wood which is loose material and in relatively large pieces. Further with such construction, the degree of penetration 20 of the grapple is dependent almost entirely upon the weight of the grapple as a whole.

One object of our invention is to provide a grapple adapted particularly for use in grasping and conveying relatively large 25 pieces of material, such, for instance, as logs, but well adapted for other uses, wherein the grapple is so formed that the blades have a penetrating and raking action without lifting action throughout a greater portion of 30 their movement into closed position.

Another object of our invention is to provide a grapple so constructed that the blades will have a penetrating action only in closing.

Still another object of our invention is to 35 provide a grapple of the above type that is relatively simple in construction and comprises a minimum number of rugged parts.

A further object of our invention is to provide a grapple of such nature that the blades 40 need not necessarily be brought to full closed position to hold certain materials satisfactorily.

Other objects of our invention may be seen in the following description and one embodiment 45 thereof may be seen in the accompanying drawings wherein similar characters of reference designate corresponding parts and wherein:

Fig. 1 is a side elevation showing a grapple 50 constructed in accordance with our invention.

Fig. 2 is a sectional view taken on the line 2—2 of Fig. 1.

Fig. 3 is a sectional view taken on the line 3—3 of Fig. 1.

Fig. 4 is a diagrammatic view showing the 55 blades of the grapple in both open and closed position.

Fig. 5 is a top plan view of the device shown in Fig. 1.

In the drawings, we have shown a grapple 60 which comprises an upper head 1 to which is secured by a cable fastening wedge 2, or other suitable means, a hoisting cable 3 by means of which the grapple is raised, lowered, or moved to any desired position. Disposed 65 radially about the outer periphery of this upper head are a plurality of depending struts or rods 4 which are pivotally mounted on the head 1, and which support, at their lower ends, a plurality of tapered blades 5 by being pivotally connected to blade supporting arms 6 as at 7. As shown, the blades 5 are so shaped that there is an open space between the side edges of each pair of adjacent blades. 70 However, the shape of the blades as to width 75 is optional.

The inner ends of the blade supporting arms 6 are each pivotally connected to a lower member or cross head 8 which is rigidly attached to the lower end of a frame 9, the 80 pivot points being substantially above the pivotal connections 7 between the blade supporting arms and the struts 4 when the grapple is closed. A grapple closing drum 10 is 85 rotatably mounted within the frame 9, as shown in Figs. 1 and 2, by being rigidly mounted on a shaft 11 that is journaled in bearings 12 in opposing sides of the frame 9. As shown in Fig. 1, a guard 13 is disposed 90 about the major portion of the drum and, as shown in Fig. 2, the uppermost end of the frame 9 is provided with a bumper element 14 that strikes against the under side of the upper head 1 and a cable guard 15 which prevents the cable 22 from slipping off of the 95 drum 10.

Cam shaped spools 16 are rigidly mounted 100 on opposing ends of the shaft 11 which extends outwardly from opposing sides of the frame 9 by means of keys 17 adapted to fit

within keyways 18 in the shaft and spools and these cam shaped spools have the ends of chains 19 rigidly attached thereto, as at 20, and pivotally attached to the head 1, as 5 at 21, at their opposing ends.

As shown in Fig. 1, a chain or cable 22 passes downwardly through the head 1 around a guide sheave 23 and thence around the drum 10, the free end of the cable being 10 rigidly attached to the periphery of the drum in any well known manner.

In the operation of this device, when it is desired to cause the blades 5 to separate to the full line position shown in Fig. 4, the 15 cable 22 is released so that the frame 9 with its composite parts, which includes the lower or cross head 8, will drop downwardly by its own weight, whereby the inner ends of the supporting arms 6 will be moved downwardly, the arms rotated about their pivotal connection 7 with the struts or rods 4, and the blades 5 will be moved outwardly to the full line position as shown in the figure, the cable 22 winding up on the drum 10 and the chains 25 19 unwinding from the cam shaped spools 16. Reversely, the blades being in open position, to cause convergence of the blades, upward force is exerted on the cable 22 whereby such cable will be unwound from the drum 10, 30 rotation of the drum 10 causing rotation of the cam shaped spools 16 and a winding up of the chain 19 on such spools, whereby the frame and composite parts, including the lower cross head 8 will be moved upwardly 35 until the frame bumper 14 abuts against the lower surface of the head 1, at which time the blades will be in closed position.

In accordance with our invention, the 40 blades 5 are so disposed relatively to their supporting arms 6 that the angle between the blades and the supporting arms is obtuse. That is, the pivot points 27 between the blade supporting arm 6 and the cross head 8, when the blades 5 are in closed position, are above 45 the centers of curvature of the blades 5 which will produce obtuse angles at the intersection of lines drawn through the two pivot points of each supporting arm, indicated at 25, and continuations of the lines of the curvature of 50 the blades, as at 26. This is clearly shown by the angle A in Fig. 4. With this construction, as shown in Fig. 4, movement of the 55 points of the blades towards each other in closing of the grapple will result in, first, a penetrating action and then a raking movement of the blades. However, in closed position, the points of the blades are in a substantially lower plane than that which they 60 occupy in open position. Also, in accordance 65 with our invention, the blade supporting arms are so rounded on their interior surface that the material being raked inwardly by the converging movement of the blades will be rolled upwardly toward the top of the 70 grapple.

With such construction, numerous novel and advantageous features arise. One of these features arises from the fact that the angles between the blades and their supporting arms are obtuse. Thus a greater distance 70 between open blade points is secured while, at the same time, the blades, on converging toward closed position, move with a penetrating and then a raking action relative to the material. Still another advantage arises 75 from the fact that the inner surfaces of the blade supporting arms are rounded whereby it is possible to obtain a full load of loose 80 relatively large material at each operation of the grapple in a contra-distinction to previous types of grapples. A further advantageous feature of the invention resides in the fact that we have provided a grapple wherein it is not necessary that the blades be brought to full closed position to hold certain 85 materials such, for instance, as logs satisfactorily. This is due, primarily, to the relative position of the blades as regards their supporting arms and the position of the lower or cross head to which the supporting arms 90 are pivotally connected.

What we claim is:

1. A device of the character described comprising an upper head, means connected thereto for making an operative connection with a grapple lifting means, a lower head movable relative to said upper head and having means connected therewith for moving said lower head towards and away from said upper head to bring about a closing and opening of said grapple, a plurality of struts pivotally connected to said upper head and depending downwardly therefrom, a plurality of curved blades, and blade supporting arms curved generally with the same curvature as 100 that of the blades pivotally connected to said lower head and to the lower ends of said struts, the angle between a line drawn from the free point of each blade and the point of connection between the blade supporting arm 105 and a strut and a line drawn through the pivotal points of the blade supporting arm being such that the free points of the blades are in a plane at a lower level when in closed position than the plane they occupy in open position.

2. A device of the character described comprising an upper head, means connected thereto for making an operative connection with a grapple lifting means, a lower head movable 115 relative to said upper head and having means connected therewith for moving said lower head towards and away from said upper head to bring about a closing and opening of said grapple, a plurality of struts pivotally connected to said upper head and depending downwardly therefrom, a plurality of curved 120 blades, and blade supporting arms curved generally with the same curvature as that of the blades pivotally connected to said lower 125 head.

head and to the lower ends of said struts, the angle between a line drawn from the free point of each blade and the point of connection between the blade supporting arm and a 5 strut and a line drawn through the pivotal points of the blade supporting arm being such that the free points of the blades are in a plane at a lower level when in closed position than the plane they occupy in open 10 position, and such that the lower head is in substantially the same plane as the free points of the blades when the grapple is in open position.

3. A device of the character described comprising an upper head, means connected thereto for making an operative connection with a grapple lifting means, a lower head movable relative to said upper head and having means connected therewith for moving 15 said lower head towards and away from said upper head to bring about a closing and opening of said grapple, a plurality of struts pivotally connected to said upper head and depending downwardly therefrom, a plurality 20 of curved blades, and blade supporting arms curved generally with the same curvature as that of the blades pivotally connected to said lower head towards and away from said upper head to bring about a closing and opening of said grapple, a plurality of struts pivotally connected to said upper head and depending downwardly therefrom, a plurality 25 of curved blades, and blade supporting arms curved generally with the same curvature as that of the blades pivotally connected to said lower end and to the lower ends of said struts, the angle between a line drawn from the free 30 point of each blade and the point of connection between the blade supporting arm and a strut and a line drawn through the pivotal points of the blade supporting arm being such that the free points of the blades are in 35 a plane at a lower level when in closed position than the plane they occupy in open position, and such that there will be no upward movement of the blade points until the horizontal center line of the lower head and the 40 pivotal connections between the blade supporting arms and the struts are in substantially the same horizontal plane.

4. A device of the character described comprising an upper head, means connected thereto for making an operative connection with a grapple lifting means, a lower head movable relative to said upper head and having means connected therewith for moving 45 said lower head towards and away from said upper head to bring about a closing and opening of said grapple, a plurality of struts pivotally connected to said upper head and depending downwardly therefrom, a plurality of curved blades, and blade supporting arms 55 curved generally with the same curvature as that of the blades pivotally connected to said lower head and to the lower ends of said struts, the angle between a line drawn from the free point of each blade and the point of 60 connection between the blade supporting arm and a strut and a line drawn through the pivotal points of the blade supporting arm being such that, in closing, the blades move with a 65 penetrating, then a raking, and then a lifting action.

5. A device of the character described comprising an upper head, means connected thereto for making an operative connection with a grapple lifting means, a lower head movable relative to said upper head and having means connected therewith for moving 70 said lower head towards and away from said upper head to bring about a closing and opening of said grapple, a plurality of struts pivotally connected to said upper head and depending downwardly therefrom, a plurality of curved blades, and blade supporting arms curved generally with the same curvature as that of the blades pivotally connected to said lower head and to the lower ends of said struts, the angle between a line drawn from the free point of each blade and the point of connection between the blade supporting arm and a strut and a line drawn through the pivotal 75 points of the blade supporting arm being such that the free points of the blades are in a plane at a lower level when in closed position than the plane they occupy in open position, and such that, in closing, the blades move with a penetrating, then a raking, and then a lifting action. 80

In testimony whereof we hereby affix our signatures.
